PHONOGRAPH CABINET

Robert A. O'Neil, Glen Ellyn, Ill., assignor to The
Seeburg Corporation of Delaware, Chicago, Ill.

Filed Aug. 12, 1970, Ser. No. 24,456

Term of patent 14 years

Int. Cl. D14—01

U.S. Cl. D56—4

FIG. 1 is a front, top and right side perspective view of a phonograph cabinet, showing my new design;

FIG. 2 is a fragmentary front elevational view, the upper portion being omitted for convenience in illustration;

FIG. 3 is a right side elevational view, the left side being substantially a mirror image thereof;

FIG. 4 is a top plan view; and

FIG. 5 is a top, front perspective view thereof.

The rear and bottom, not shown, are plain and unornamented. Portions of the drawing figures are diagonally lined to indicate transparency.

I claim:

The ornamental design for a phonograph cabinet, substantially as shown and described.
